[57] **CLAIM**

The ornamental design for an electronic apparatus housing, as shown and described.

DESCRIPTION

FIG. 1 is a top perspective view closed of the electronic apparatus housing, showing my new design;

FIG. 2 is a top perspective view open thereof the broken lines being shown for illustrative purposes only and form no part of the claimed design;

FIG. 3 is a left side elevation view closed thereof on an enlarged scale;

FIG. 4 is a top plan view closed thereof;

FIG. 5 is a front elevation thereof;

FIG. 6 is a rear elevation thereof;

FIG. 7 is a bottom view thereof; and,

FIG. 8 is a left side elevation view open thereof. The right side of the design is a mirror-image of the left side.

FIG. 1**FIG. 2****FIG. 3****FIG. 4****FIG. 5****FIG. 6****FIG. 7****FIG. 8**
